ATTORNEY.

UNITED STATES PATENT OFFICE.

SAMUEL F. MILLER, OF BRIDGEWATER, VIRGINIA.

FLOOD-FENCE.

SPECIFICATION forming part of Letters Patent No. 607,568, dated July 19, 1898.

Application filed December 10, 1897. Serial No. 661,351. (No model.)

To all whom it may concern:

Be it known that I, SAMUEL F. MILLER, a citizen of the United States, residing near Bridgewater, in the county of Rockingham 5 and State of Virginia, have invented certain new and useful Improvements in Flood-Fences; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to fences for use on lands subject to overflow, and is designed to fall horizontally with the first rush of the waters, no part of it then appearing more than a few inches above the ground. It 20 does not catch rubbish and drift-wood and is easily erected again when the waters have subsided. The fence is also removable, as each panel is portable and complete in itself.

The various features of the invention are 25 illustrated in the accompanying drawings, in which—

Figure 1 is a front view with the fence in vertical position. Fig. 2 is an edge view of a panel in vertical position. Fig. 3 is an end 30 of a panel in the act of falling from the force of the water, and Fig. 4 is a like view with the fence prostrate.

Similar letters denote corresponding parts in the various views.

The letters A A indicate the end posts, and B B the bars, of a panel or section of my fence. Each panel is distinct and separate from the others and should be firmly put together. In its construction I prefer to make a long 40 panel with a center post A' and two braces a a; but any preferred framing may be used. The boards at the bottom should be put closely together to receive at once the full force of the water, and so to fall before rubbish and drift-wood are collected against them. The drift will then pass over the fence and float away into natural channels. At a 45 proper distance from the fence short anchor-posts C C are fixed in the ground, to which

and to the end posts A A are pivotally attached braces D D, their connection with the fence-posts being at a point above the middle and preferably about two-thirds of the height of the post from the ground.

When set up, the weight of the fence and the braces D D will secure it against derangement by large cattle and ordinary wind, and to prevent small stock from disturbing it lock bars or rods E E are pivotally attached to the lower ends of the fence-posts and provided with hooks e e to engage pins f f on the anchor-posts. These would resist pressure from the anchor-post side and would permit the fence to fall from pressure on the opposite or flood side.

In a violent wind, sufficient to demolish rigid fences, this fence would fall and escape injury in the same manner as when thrown by the water. It is also evident that the fence can be readily shifted from one side 70 to the other of the line of anchor-posts, and so afford minor advantages not necessary to particularize herein.

What I claim, and desire to secure, is—

1. A flood-fence formed in sections whose 75 end posts above the middle, are pivotally connected by arms to anchor-posts, as herein described.

2. A flood-fence formed in sections, to whose end posts above their middle, are pivoted the ends of bracing-arms, whose other ends are pivotally connected to anchor-posts, and lock-rods, detachably connecting the lower ends of said end posts to said anchor-posts substantially as described.

3. A flood-fence having panels formed of two end posts A, A, a center post A', bars B, B, and frame-braces a, a, supporting-braces D, D, pivoted at one end to said panels above their middle, and at the other end to anchor-posts C, C, and lock-bars E, E, for the purpose herein described.

In testimony whereof I affix my signature in presence of two witnesses.

SAMUEL F. MILLER.
